UNITED STATES PATENT OFFICE

160,522

AUTOMOTIVE VEHICLE BUMPER

Ned F. Nickles, Detroit, Mich., assignor to General Motors Corporation, Detroit, Mich., a corporation of Delaware

Application August 10, 1949, Serial No. 4,400

Term of patent 3½ years

(Cl. D14—6)

To all whom it may concern:

Be it known that I, Ned F. Nickles, a citizen of the United States, being a resident of Detroit, county of Wayne, State of Michigan, have invented a new, original, and ornamental Design for an Automotive Vehicle Bumper, of which the following is a specification, reference being made to the accompanying drawing, forming a part thereof.

In the drawing:

Figure 1 is a perspective view of an automotive vehicle bumper having a design in accordance with my invention, the parts of the vehicle body shown in dotted lines being for illustrative purposes only.

Figure 2 is a top plan view thereof.

Figure 3 is a front elevational view thereof.

Figure 4 is a sectional view taken on line 4—4 of Figure 2 the parts remotely to the left

of line 4—4 of Figure 2 being deleted from the view.

The dominant features of my design are shown in solid lines.

I claim:

The ornamental design for an automotive vehicle bumper, substantially as shown and described.

NED F. NICKLES.
